CLAIM

The ornamental design for a table lamp, as shown and described.

DESCRIPTION

FIG. 1 is a perspective view of a table lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2; and,

FIG. 11 is a perspective view of the table lamp where the table lamp is in a configuration of use.

The dash-dash broken lines immediately adjacent to the shaded areas depict the bounds of the claimed design, while all other dash-dash broken lines are directed to environment. The dot-dash broken lines represent boundaries of the enlarged portions. The broken lines form no part of the claimed design.

1 Claim, 11 Drawing Sheets
